UNITED STATES PATENT OFFICE.

GEORGE W. KRETZSCHMAR, OF PASSAIC, NEW JERSEY.

BOBBIN-HOLDER.

1,233,064.

Specification of Letters Patent. Patented July 10, 1917.

Application filed September 25, 1916. Serial No. 121,944.

To all whom it may concern:

Be it known that I, GEORGE W. KRETZSCHMAR, a citizen of the United States, and a resident of Passaic, in the county of Passaic and State of New Jersey, have invented certain new and useful Improvements in Bobbin-Holders, of which the following is a specification.

This invention relates to improvements 10 in bobbin holders of the types used in connection with warping machines, twisting frames, yarn reels and other allied mechanisms wherein a number of fine yarns are to be united into a single strand.

15 The principal object of the invention is to provide a form of bobbin holder or flier capable of long and extended use and which consumes a minimum of power to operate such as may be conveyed by the extremely 20 light and fragile yarn wound upon the bobbins.

Another object is to provide such holders 25 with means which resiliently engage with the interior of the cop or bobbin holding it in position, and further to provide means which are susceptible of holding the cops or bobbins in any desired arrangement either in a straight horizontal line or disposed in curves or angles.

30 These and other like objects are attained by the novel construction and combination of parts hereafter described and shown in the accompanying drawings, forming a material part of this disclosure, and in which:—

35 Figure 1 is a vertical sectional view showing the holder on its support as applied to a form of cop tube.

Fig. 2 is a perspective view showing the holder in detail.

40 Fig. 3 is a vertical view taken through the center of the holder.

Fig. 4 is a transverse sectional view taken on line 4—4 of Fig. 1.

Fig. 5 is a vertical sectional view showing 45 a further modification.

Fig. 6 is a similar vertical sectional view showing a modified means of engaging the holder to its stand.

Fig. 7 is another like sectional view of 50 the same, and

Fig. 8 is a diagrammatic view illustrating the relative position of the bobbins to a set of feed rolls.

55 In all twisting and spinning machines the spools revolve on spindles mounted on the frames and these spindles must turn easily

in order to avoid stretching the fibers between the spool and cylinder.

Especially is this true where fine material is spun or twisted, as in the case with 60 silk, wool and cotton, where it is exceedingly difficult to produce a uniform thread due to the unsteady run of the spool and the variation in stretching of the fibers caused by the unequal tension on the same.

65 Referring now to the drawings, a fixed rail 10 forms a portion of the supporting frame, the same being embraced in a forked metal element 11 whereby the necessary strength and stiffness is attained.

70 Rigidly set in the upper portion of the element 11, at uniform distances apart, are studs 14 preferably formed with a flange 15 immediately above which is a neck portion 16, the lower bearing 17 extending 75 thereabove, and a straight cylindrical stem element 18 extends to the upper bearing 19, the stem 18 being of reduced diameter so as to decrease the frictional resistance of the tubular sleeve 20 which envelops it.

80 Formed with the sleeve is a flange 21 having a diameter slightly greater than that of the cop or spool to be placed on the device: formed with the opening through the flange are lips 22 adapted to be spun inwardly toward a common center and engage with the neck 16 so as to prevent the sleeve from rising. At the upper end of the sleeve is an integral head 23 formed with a screw-thread at its center and provided with an adjusting screw 25 having a clamp or lock nut 26 to hold the same when adjusted so that its extreme point enters 85 into a corresponding conical recess formed centrally in the top of the bearing 19 thereby permitting a moderate latitude of vertical motion of the sleeve relative to the support.

90 Rigidly secured to the head 23 of the sleeve, at equally-distant points, are a plurality of resilient wires 28 of any preferred cross sections, preferably three in number, so as to exert a uniform pressure in all directions within the hollow sleeve, cop or spool 30 upon which the sliver or yarn 31 105 is wound.

95 The lower ends of the spring elements pass through appropriate openings 33, formed with the flange element 21, preventing the same from displacement at their lower ends and also increasing the resiliency of the wires.

The construction of the foregoing parts is clearly evident from inspection of Figs. 1 and 2 of the drawings; this arrangement is preferred where relatively strong, 5 heavy material is wound upon the cops as by the use of the set screw friction may be produced as desired tending to overcome too free rotative action of the cop.

In Fig. 3 an annular recess 35 is formed 10 in the stem 18, the sleeve 20 being provided with a raised boss 36 adapted to contain a screw 37, the cylindrical point 38 of which enters the recess 35 thereby holding the sleeve against longitudinal motion relative 15 to the stem 18 in either direction.

In the adaptation shown in Fig. 5 a pin 40 is rigidly inserted in the head 23 acting in a manner similar to that of the screw 25. A similar but reversed arrangement is indicated in Fig. 6 in which a set screw 42 is provided, formed with an inverted conical point adapted to receive the cone 43 formed above the bearing 19 of the stem 18.

In Fig. 7 is shown a variation consisting 25 of a solid head 23 formed with the sleeve 20 containing the spindle 18 with its bearings 17 and 19 respectively, the sleeve being maintained in operative position on the stem by reason of an annular slot 45 being formed 30 therein, and the metal of the sleeve rolled or spun, as at 46 so as to engage within the annular recess 45 as will clearly be evident.

Fig. 8 shows an arrangement of spools 35 disposed in an arc of a circle and in such manner that the yarn is drawn to a central point therefrom passing through rolls where the several fibers are united into a single strand and thence to a spinning frame or cylinder.

40 These arrangements permit of extremely fragile yarns to be withdrawn from the spools with the least danger of breakage possible.

In operation the cop, tube or spool having been filled with the fibers in the form of a thin yarn or sliver, it is placed over the several springs 28 the same being extended outwardly tending to hold the spool in a relatively rigid manner, the lower end of 50 the spool being formed squarely across and adapted to rest upon the flange 21 whereby it is measurably prevented from lateral

movement in any direction and caused to rotate upon the central axial plane of the stem.

From the foregoing it will be evident that the use of oil is unnecessary or used in the most limited quantity, and that the parts are so constructed that should oil be used, it is prevented from making contact with 60 the yarn or threads upon the cops, and the arrangement is such that the cops may be held at an angle of as much as 45 degrees in either direction thereby permitting the cops to be unwound perpendicular to their rotation, the arrangement being such that the frame is less crowded than usual and the whole structure lowered, thus increasing the efficiency of the employee.

Having thus described my invention what 70 I claim as new and desire to secure by Letters Patent, is:—

1. In a cop support, the combination with a frame, a plurality of hardened spindles secured to said frame, sleeves mounted on 75 said spindles, means for holding said sleeves engaged therewith, a flange formed at the base of said sleeves upon which the cop may rest, an integrally formed annular head, the periphery of which extends beyond the body 80 of said sleeve, a plurality of arcuately bent resilient wires attached at both ends of said sleeves adapted to engage within the cop, and means for tensionally adjusting the frictional resistance between said sleeves and 85 said spindles.

2. In a cop holder, the combination with a hardened spindle having bearing surfaces at opposite ends, a sleeve surrounding said spindle, means for engaging said sleeve to 90 said spindle, an annular flange formed integral with said sleeve adapted to support a cop, a solid enlarged head formed with said sleeve and a plurality of resilient curved wires attached to said head their lower ends 95 passing freely through openings formed in said flange, said resilient wires being adapted to tensionally engage with the interior of the cop.

Signed at Passaic, in the county of Pas- 100 saic and State of New Jersey, this 15 day of September, 1916.

GEO. W. KRETZSCHMAR.
